HORIZONTALLY FLOATING CAR COUPLER

Paul C. Koch, New Haven, Conn., assignor to The
 A. C. Gilbert Company, New Haven, Conn., a
 corporation of Maryland

Application October 28, 1938, Serial No. 237,427

9 Claims. (Cl. 213—104)

This invention relates to draft rigging for toy railways and more particularly to means for coupling and uncoupling adjacent cars of a toy train as a consequence of movement or approach 5 of the cars along curved stretches of track as well as along straight stretches of track.

In coupling devices for this purpose it has heretofore been the custom to bias by spring means or variably to station by linkage movement, the interlocking coupler parts in definitely predetermined positions for proper cooperation corresponding to different degrees of swinging of the wheel truck away from straight alignment with the longitudinal center line of the car. 10

Such means have been considered necessary to enable cars which are rounding a curve to be coupled together. This has involved complexity 15 of mechanism and parts of fragile nature which are highly undesirable in toy cars whose mechanisms are exposed to abuse through careless handling by children and thereby easily damaged.

One object of this invention is to provide coupling parts capable of interlocking merely as the 20 result of approaching movement of adjacent cars, capable of accommodating themselves to the relative swinging of the coupled cars when rounding curves in the track, and requiring no biasing means nor linkage actuating means for 25 positioning the coupling parts thereby to simplify and render more rugged the construction of such parts and reduce their cost of manufacture.

A further object is to employ coupling parts having these capabilities which are identical at 30 each end of each car thereby to make universal the ability of either end of any car to be automatically coupled with either end of any other car having a like coupling or with a toy locomotive or other piece of toy rolling stock.

40 A further object is to provide coupling devices having these characteristics which will lend themselves to ready manual uncoupling, or to automatic uncoupling as a result of two coupled cars passing an uncoupling station positioned at 45 any desired point along the track.

The foregoing and other objects of the present improvements will appear in greater particular in the following description of possible forms of embodiment thereof illustrated in the accompanying drawings, wherein:

Fig. 1 is a plan view of the end portions of the platforms of two cars coupled together by devices embodying the present improvements and adapted to travel along a curved stretch of track.

55 Fig. 2 is a bottom plan view looking upward

at the end portion and one car and coupler of Fig. 1.

Fig. 3 is a view taken in section on the planes 3—3 in Fig. 2 looking in the direction of the arrows and showing the track.

Fig. 4 is a view looking from the right toward the end of the car in Fig. 3, both track rails appearing in cross section.

Fig. 5 is an enlarged view of the floating 10 coupler part taken in section on the planes 5—5 in Fig. 1.

Fig. 6 is plan view of companion coupling parts of adjacent cars shown on the same scale as in Fig. 5, these parts appearing in one of the 15 relative positions they may occupy when first brought into contact upon approach of the cars before the couplers have interlocked.

Figs. 7 and 8 show respectively the relative 20 positions which the parts in Fig. 6 successively assume during their automatic coupling action.

Fig. 9 is a plan view similar to Fig. 6 showing the companion coupling parts of adjacent cars in different relative positions which they may occupy when first brought into contact upon 25 approach of the cars.

Figs. 10, 11 and 12 show respectively the relative 30 positions which the parts of Fig. 9 successively assume during their automatic coupling action.

Fig. 13 is an enlarged view of the end portions 35 of adjacent cars and track showing in side elevation a modified construction of the coupling devices which enables them to be automatically uncoupled or manually uncoupled from a point beside the track, the car platform and truck and 40 certain other parts appearing in central vertical section on the plane 13—13 in Fig. 14 looking in the direction of the arrows.

Fig. 14 is a view taken in section on the plane 45 14—14 in Fig. 13 looking in the direction of the arrows, the truck, wheels and track being omitted.

As the problems of mechanical action which confront successful automatic coupling of cars 50 are much more complicated upon curved stretches of track than upon a straight track, the car platforms 10 and 11 of Fig. 1 are shown on curved track with their respective trucks 12 and 13 angularly related as determined by their respective flanged wheels 14 and 15 engaging the 55 curved stretch of track 16 which is supported by the spaced sleepers 31.

The showing of the end portions of cars 10 and 11 in Fig. 1 assumes identical construction of both cars and of both trucks, such as may be

duplicated at each end of every car, locomotive, or other piece of rolling stock comprising the toy train. The interengageable coupling devices may likewise be identical, in each case including 5 the simple hook-like part designated as a whole by 17 pivotally connected by the rivet 18 to the free end of the draw bar 19 whose other end is fast to the truck so that the draw bar 19 swings in unison with the truck. A tongue 21 struck 10 down from the circularly ribbed table 22 of the truck enters and snugly fits an aperture 23 in the draw bar to insure this result. The end apron 32 of each car contains a horizontally elongated aperture 33 in which the draw bar 19 15 freely swings relative to the car in unison with the swinging movement of the truck relative to the car.

The free end of draw bar 19, as best shown in Figs. 5 and 6, terminates in spaced bent-up lugs 20 24, 25 between which the draw arm 26 of the coupler 17 is free to float or swing without bias in a horizontal plane between limits determined by said lugs. The cam-like reactive portions of the coupler 17 include a tail piece 27 and a rounded 25 head 28 terminating in the abruptly hooked nose 29, all of which portions are stiffened by the externally projecting rib 30 which extends horizontally throughout these portions. Thus the coupler may, if desired, be made from thin and 30 light-weight sheet metal.

For convenience in describing the action and reaction of cooperative couplers in Figs. 1 and 6 to 12 inclusive, the above described parts of the coupler of car 10 are respectively indicated by 35 the same reference numerals primed in the case of the coupler 17' of car 11.

The operation of the coupling devices of Figs. 1 to 12, inclusive, will be described with particular reference to Figs. 1 and 6 to 12 inclusive. The 40 broken lines A—A and B—B in the last said group of figures indicate a typical angular relationship of trucks when approaching on a curved stretch of track. Thus these lines also approximate the direction of movement of the pivots 18 and 18' toward each other at the time the parts are positioned as shown in each of these figures. In Fig. 6 it is assumed that in the absence of means to bias the arm 26 either toward lug 24 or toward lug 25, and in the absence of means to bias the arm 26' in either direction either toward lug 24' or toward lug 25', that these arms 26 and 26' may arbitrarily be related as shown in Fig. 6 upon the coming into contact of tail piece 27' of coupler 17' with the rounded head 28 of coupler 17. The 45 consequent thrust against tail 27' as the cars continue to approach each other will result in a tendency of coupler 17' to swing counterclockwise about its pivot 18' and will result in a simultaneous tendency of coupler 17 to swing counterclockwise about its pivot 18. As this tendency to swing is more pronounced upon coupler 17' than upon coupler 17 at the beginning of the approach, the arm 26' will be swung over into engagement with lug 25', as shown in Fig. 7, as 50 the rounded head 28' travels into contact with the tail piece 27. Continued approaching travel of the pivots 18 and 18' with their respective car trucks will result in rounded head 28' forcing the arm 26 to swing over into engagement 55 with lug 25 because of the pressure thus exerted on tail piece 27 so that the parts will assume the positions shown in Fig. 8. Here the cars have approached the limit permitted by the coupling device and upon subsequent separating travel of 60 the cars, couplers 17 and 17' will securely inter-

lock as shown in Fig. 1 being prevented from slipping out of impelling engagement by the hooked nose pieces 29 and 29'.

In Fig. 9 it is assumed that the couplers 17 and 17' happen to be related differently than in Fig. 6 when they are first brought into contact for intercoupling. Here, because the arm 26 is against the lug 25 and because the arm 26' is against the lug 25', the initial contact is between the rounded heads 28 and 28' of the two couplers. 10 Pressure between these contacting surfaces reacts in a direction normal thereto and sets up a tendency of coupling 17 to swing clockwise about its pivot 18 and a simultaneous tendency of coupling 17' to swing clockwise about its pivot 18' so that the parts move into their positions shown in Fig. 10. Continued approach of pivots 15 18 and 18' with their respective cars results in the tail piece 27' contacting the rounded head 28 and the tail piece 27 contacting the rounded 20 head 28'. This imparts, as described in connection with Figs. 6 to 8, a contrary or counterclockwise rotation of the couplers about their respective pivots which brings the couplers into their relationship shown in Fig. 12 after which separating movement of the cars will result in the 25 interlocking of the couplers indicated in Fig. 1.

With particular reference to Fig. 9 it is pointed out that if the cars were aligned on a straight stretch of track with the bars 26 and 26' midway each pair of lugs 24, 25 and 24', 25', respectively, the presence of angle X in the disposition of the coupling surfaces which would then engage will cause the pressure of each coupling head upon the other to cam both couplings clockwise about 35 their respective pivots and thus avoid dead centering of the line of pressure of either coupling against the other with respect to the coupler pivots 18 and 18'.

From the foregoing description of operation 40 it is seen that coupling devices embodying the present principles of cooperative shape and mounted disposition will accommodate their draft action to all of the variety of angular positions to which they may have to swing as the cars 45 travel over straight tracks and tracks of varying curvature and without cramping under any circumstances. The hooked ends 29 and 29' prevent accidental uncoupling. They will likewise accommodate their coupling action to considerable lack of designed accuracy in the relationship of the trucks and of the draw bars 19 and 19' as is bound to be encountered in the inexpensive construction and desirable looseness characteristic of toy trains. At the same time no spring or 55 other form of biasing mechanism is required, and no predetermined definite positioning of the cooperative couplers by complicated linkage movement is needed such as has heretofore complicated the structure of toy car couplers. 60

In the modified construction of Figs. 13 and 14 corresponding parts are similarly designated. Here the end apron 34 of the car and its aperture 35 is made deeper than the apron 32 and aperture 33 in Figs. 1 to 4 inclusive, while the 65 truck pivot pin 36 and lock tongue 37 for the modified draw bar 38 are made longer to produce an axial looseness which permits draw bar 38 upon occasion to be tilted upwardly from its full line position to its broken line position in Fig. 13 70 thereby automatically or manually to effect uncoupling of the engaged parts 17 and 17' which may be constructed as in Figs. 1 to 12 inclusive. During this action tongue 37 continues at all times in engagement with slot 23 to maintain 75

the rotative interlock between truck table 22 and draw bar 38.

Means for manual as well as automatic uncoupling is provided in the lever 39 having handle portion 40 and retained pivotally under the head 41 of a stud 42 rigid with and projecting from the car apron 34 so that its opposite downwardly inclined end 43, which is slidably confined between the arcuate guide strip 44 and the car 10 apron, projects laterally beyond the car and over the track. Gravity normally maintains lever 39 in its full line position. Spanning two adjacent sleepers 31, and mounted rigidly thereon, the inclined uncoupling riser 45 lies in the path of 15 the end portion 43 of the uncoupling lever 39 so that when the car passes this riser the lever 39 is tilted upwardly and automatically from its full line position to its broken line position in Fig. 14. As lever 39 at all times underlies the 20 free end of draw bar 38, the latter is correspondingly tilted to its broken line position in Fig. 13 as permitted by the axial looseness at the truck pivot 36 thereby to effect disengagement of the 25 couplers at whatever point along the track the riser 45 is stationed. It will be seen that this automatic uncoupling can as well take place at a point along a curved stretch of track as along a straight stretch of track.

Either of additional holes 46, 47 and the additional connecting slots 48, 49 in the draw bar 19 in Fig. 2 may be occupied by the truck pivot 20 and tongue 21 to render the draw bar suitable for use on cars whose end aprons 32 are spaced a less distance from pivot 20 longitudinally of 35 the car.

Many modifications of the exact shapes and constructions herein illustrated and described are possible within the underlying principles taught by this invention and the appended claims are therefore intended to include all equivalents of such shapes and constructions which fairly come within their terms.

I claim:

45 1. In toy car construction in combination, a wheel truck having a car carrying table, a car floor structure resting on said table having an end apron containing a horizontally elongated aperture of limited vertical height, a draw bar 50 beneath said carrying table of the wheel truck projecting from the latter and through said aperture in said apron, a coupler carried by said draw bar on the opposite side of said apron from said truck, a pivot device extending through the 55 truck table the car floor and the draw bar, and means preventing the horizontal swinging of said draw bar relative to said truck constructed and arranged to permit tilting of said draw bar relative to said truck table thereby to permit said draw bar to be elevated in said apron aperture sufficiently to effect disengagement of said coupler with respect to the corresponding coupler of an adjacent car.

2. In toy car construction the combination defined in claim 1, together with a lever tilttable 65 in a vertical plane extending crosswise the said car floor structure pivotally connected to the said end apron of the car and positioned to underlie the said draw bar, thereby when tilted upward in said plane to lift the said coupler sufficiently to effect its said disengagement from the corresponding coupler of an adjacent car.

3. In toy car construction the combination defined in claim 1, together with a lever tilttable 75 in a vertical plane extending crosswise the said

car floor structure pivotally connected to the said apron of the car and positioned to underlie the said draw bar, thereby when tilted upward in said plane to lift the said coupler sufficiently to effect its said disengagement from the corresponding coupler of an adjacent car, and an inclined riser stationed beside the path of travel of adjacent coupled cars, said tilttable lever extending to a position for riding into contact with said riser thereby to be lifted by the latter 10 to uncoupling position during travel of the car past said riser.

4. An automatic coupling including horizontally interacting springless devices for connecting together the bodies of toy railroad cars, 15 embodying the combination with track guided wheel trucks pivotally carrying respective adjacent car bodies, of a draw bar supported by each of said trucks in a manner to be caused to swing in unison therewith in pivotal relation to the 20 car body, hook-like horizontally floating couplers, connections loosely holding each coupler on the end of its respective draw bar in a manner to be unbiased and free for unresisted horizontal 25 shifting between limit positions through a designed range of movement relative to said draw bar, said couplers being so constructed and cooperatively arranged that they meet and exert upon each other mutually reactive forces urging 30 both couplers to move into interlocked relationship as a mere consequence of the closing together of two cars on either straight or curved track.

5. An automatic coupling including horizontally interacting springless devices for connecting together the bodies of toy railroad cars, 35 embodying the combination with track guided wheel trucks pivotally carrying respective adjacent car bodies, of a draw bar supported by each of said trucks in a manner to be caused to swing in unison therewith in pivotal relation to the car 40 body, hook-like horizontally floating couplers, a pivotal connection holding each coupler on the end of its respective draw bar in a manner to be unbiased and free for unresisted horizontal shifting between limit positions through a designed 45 range of swinging movement relative to said draw bar, said couplers being so constructed and cooperatively arranged that they meet and exert upon each other mutually reactive forces urging one coupler to swing first outwardly and then inwardly for moving both couplers into interlocked relationship as a mere consequence of the closing together of two cars on either straight or curved track.

6. An automatic coupling as defined in claim 5, together with two stop abutments carried by the said draw arm at opposite sides of each of said couplers and projecting into the path thereof, said abutments being laterally spaced and positioned to define a range of unresisted coupler swinging movement small enough to insure the ability of said couplers to meet and exert upon each other the said reactive forces when the said two cars close together on straight track and 60 large enough to permit said couplers to meet and exert upon each other the said reactive forces when said cars close together on curved track.

7. An automatic coupling as defined in claim 5 in which each of the said couplers comprises a 70 draw arm pivoted to the said draw bar and extending beyond the end thereof, each of said draw arms carrying a curved strip of stiff material so formed and disposed that one full edge thereof is upwardly presented and defines a 75

C-shaped figure located on one side of the longitudinal center of said draw arm which figure terminates in a projecting end extending well beyond the opening in said C-shaped figure on 5 the opposite side of said longitudinal center for assisting said couplers to meet and exert upon each other the said mutually reactive forces.

8. In toy car construction, in combination, a wheel truck having a car carrying table, a draw 10 bar face-to-face with the under surface of said table and projecting from the wheel truck, and a pivot device extending through the truck table and the draw bar constructed to hold the same axially together in a manner to permit free 15 swinging movement and limited tilting movement of said draw bar relative to said truck, said truck table having a projecting tongue and said draw bar having a hole engageable by said pivot device together with a slot engageable by said 20 tongue in a manner to permit said tilting movement and to prevent relative swinging movement between said truck table and said draw bar.

9. In toy car construction, in combination, a wheel truck having a car carrying table, a car floor structure resting on said table, a draw bar beneath said carrying table of the wheel truck extending therefrom toward the end of said car 5 structure, a horizontal guideway constructed and disposed to help support said draw bar in a manner to permit both horizontal swinging and vertical tilting thereof, a coupler carried by said draw bar on the opposite side of said guideway 10 from said truck, a pivot device extending through the truck table the car floor and the draw bar, and means preventing horizontal swinging of said draw bar relative to said truck otherwise 15 constructed and arranged to permit vertical tilting of said draw bar relative to said truck table thereby to permit said draw bar to be moved vertically relative to said guideway sufficiently to effect disengagement of said coupler with respect to the corresponding coupler of an adjacent car. 20

PAUL C. KOCH.
